UNITED STATES PATENT OFFICE

131,488

DESIGN FOR A BOOK END

Peter Dionne, Detroit, Mich.

Application January 9, 1942, Serial No. 105,084

Term of patent 14 years

To all whom it may concern:

Be it known that I, Peter Dionne, a subject of the King of England, residing at Detroit, in the county of Wayne and State of Michigan, have invented a new, original, and ornamental Design for Books Ends, of which the following is a specification, reference being had therein to the accompanying drawing, forming part thereof.

Figure 1 is a front elevational view of the book end, showing my new design; and

Figure 2 is a side elevational view thereof.

Figure 3 is a top plan view, partly in section, taken on the line 3—3 of Figure 1 and in the direction of the arrows.

I claim:

The ornamental design for a book end, as shown.

PETER DIONNE.
